His Attorney.

UNITED STATES PATENT OFFICE

2,321,678

FLUID COOLED ELECTRIC DISCHARGE
DEVICE

Donald D. Hinman, Cleveland Heights, Ohio, assignor to General Electric Company, a corporation of New York

Application March 28, 1941, Serial No. 385,721

5 Claims. (Cl. 176—124)

My invention relates to gaseous electrical discharge devices, particularly those of the type shown in U. S. Patents No. 2,202,199 to Edmund Germer and No. 2,094,694 to Cornelius Bol, et al. More particularly it relates to an improved method for cooling such devices whereby a greater power output may be obtained without softening of the envelope walls and without disturbing the desired distribution of mercury vapor in the envelope. The invention consists in the new and novel arrangement of elements hereinafter described and claimed.

In order to obtain very high luminous intensities such as are necessary in photographic projection work, for example, it is necessary to operate lamps of the above mentioned type at currents and voltages which produce high temperatures when concentrated within the relatively narrow confines of the lamp. It is generally necessary, therefore, to provide some means for artificially cooling the envelope in order to prevent softening thereof. In some cases, however, the cooling may also result in excessive cooling of certain portions, such as the end chambers, and consequently in an undesirable lowering of the mercury pressure. I have found that this defect can be eliminated by providing shielding means around the said end chambers in the manner hereinafter set forth.

It is, accordingly, an object of my invention to provide an artificially cooled lamp of the aforesaid type which shall be capable of withstanding greater energy concentration, and which shall be less subject to condensation of the metallic vapor in the end chambers thereof.

Further objects and advantages of the invention will be apparent from the following detailed description and from the accompanying drawing, the single figure of which shows a lamp constructed in accordance with the invention along with a circuit for operating the same.

Referring to the figure, the lamp 1 comprises an envelope 2 having therein an anode 3 and a cathode 4, as well as a quantity of metallic vapor such as mercury at pressures above about a quarter of an atmosphere during operation. In addition, a starting gas may be added at pressures up to several millimeters. The amount of mercury introduced will be such that at the normal operating temperature of the lamp the vapor atmosphere is unsaturated with mercury. The latter procedure is described in the Pirani, et al. application Serial No. 609,547, filed May 5, 1932. The lamp will be arranged to operate at currents above about 2 amperes, which

results in considerable heating. In order to prevent softening of the envelope under the effect of this heating, an air blast 5 arranged to direct a stream of air onto the surface of the envelope is provided. The air blast may be supplied with air under pressure by any suitable source (not shown). I have found, however, that unless shielding means such as shields 6 and 7 are provided, the end sections surrounding the electrodes become excessively cooled, with the result that the mercury condenses in the end chambers.

The end shields may comprise cylindrical members 8 provided with end portions 9 having re-entrant sleeve portions 9' which fit snugly over the envelope. These members may be of any suitable metal or insulating construction. They may be also of glass or quartz and made integral with the envelope. The effect of these end shields is to protect the end portions of the lamp from excessive cooling by the air blast 5 and thereby to raise the temperature of the said end chambers. In order to further raise the temperature, a coating 10 of metal such as platinum may be provided for the purpose of reflecting back into the envelope any heat radiation which tends to leave the end chamber. Alternatively, the caps 11 may be provided on the shield members 8 for the purpose of cutting down the end radiation. The brass ferrules 12 may be provided as external terminals for the lamp and may be cemented thereto by any suitable means.

For the purpose of energizing the lamp, I have shown a source of direct current 13 connected in series with a ballast resistor 14, a switch 15 and the lamp itself. In one case, this generator had a terminal voltage of about 240 volts, while the resistor 14 was about 55 ohms. Under these conditions, approximately 2 amperes flowed through the lamp and the voltage between the electrodes was about 130 volts.

For the purpose of completeness, the following dimensions of the aforescribed lamp system might be noted. The lamp 1 in the above case had an internal diameter of approximately 4 mm. with a spacing of about 18 mm. between the electrode tips. The cylindrical shields were about $\frac{1}{2}$ inch long and $\frac{1}{2}$ inch in diameter. The forward end portion 9 of the shield surrounding the cathode was positioned about 2 mm. ahead of the cathode tip, while the portion 9 of the shield surrounding the anode was made flush with the anode tip. If both electrodes were to serve as cathodes alternately, as in the case of

a lamp operated with alternating current, it would be well to position both of these portions 9 from 1 to 2 millimeters ahead of the tip of the corresponding electrode. The electrodes 3 and 4 were formed by winding tungsten wire of about 20 mils diameter loosely around a piece of thorium and a core comprising a 25 mil tungsten wire. Each of such coils was approximately 6 mm. long. The cathodes may, however, be of the unactivated type described and claimed in the copending application of Lyman B. Johnson, Serial No. 381,633, filed March 4, 1941.

It will be understood that many modifications in the described details of my invention may occur to those skilled in the art to which it appertains. For example, while I have stressed its use in connection with a lamp having an unsaturated mercury vapor pressure, it may also be used with the saturated vapor type, i. e., the type wherein the electrodes are formed by pools of mercury. Further, it will be understood that the invention is equally applicable to lamps of the alternating current type, although I have shown it in connection with a direct current lamp. All such modifications I aim to include in the scope of the appended claims.

What I claim as new and desire to secure by Letters Patent of the United States is:

1. In combination, an electrical discharge device comprising an elongated tubular envelope, an electrode sealed in each end of said envelope and projecting a substantial distance inwardly from the adjacent end wall of the envelope, said electrode being of smaller diameter than the surrounding envelope wall which thereby forms an electrode chamber extending a substantial distance behind the tip of the electrode, an ionizable medium in said envelope comprising

mercury, means for supplying to said device an energy loading sufficient to soften the envelope in the absence of vigorous artificial cooling, means for directing a concentrated compressed air blast at said envelope substantially midway between said electrodes at a pressure sufficient to maintain the envelope at a temperature below its softening point, and tubular shield members surrounding said electrode chambers and having closed front ends located closely adjacent to the tips of the said electrodes to prevent cooling of said end chambers by said air blast with resultant condensation of mercury in said end chambers.

2. The combination set forth in claim 1 wherein in the amount of mercury in the envelope is insufficient to saturate the atmosphere therein at the normal operating temperature of the device.

3. The combination set forth in claim 1 wherein in the front ends of the shield members have reentrant sleeve portions extending rearwardly and fitting the envelope closely.

4. The combination set forth in claim 1 wherein in the energy supply means includes a source of direct current and the front end of the shield member surrounding the cathode electrode is located a short distance ahead of the tip of that electrode while the front end of the shield member surrounding the anode electrode is located at the tip of that electrode.

5. The combination set forth in claim 1 wherein in the energy supply means includes a source of alternating current and the front ends of the shield members are located a short distance ahead of the tips of the contiguous electrodes.

DONALD D. HINMAN.
